UNITED STATES PATENT OFFICE.

HUGO O. STAMP, OF MILWAUKEE, WISCONSIN.

CONCRETE-MIXER LOADER.

1,290,797.

Specification of Letters Patent.

Patented Jan. 7, 1919.

Application filed January 23, 1915. Serial No. 3,969.

To all whom it may concern:

Be it known that I, HUGO O. STAMP, a citizen of the United States, residing at Milwaukee, in the county of Milwaukee and State of Wisconsin, have invented certain new and useful Improvements in Concrete-Mixer Loaders, of which the following is a specification.

The present invention relates to new and useful improvements in conveying apparatus wherein the various conveyer sections are relatively movable to engage the material to be conveyed, and the invention is more particularly directed to the provision of a loading machine adapted for use in connection with concrete mixers.

In various concreting operations on a relatively large scale, piles of certain of the ingredients of the concrete, or aggregate, are dumped at points adjacent the concrete mixing machine, and in road paving operations the aggregate is dumped in piles along the roadway in advance of the mixing machine. A considerable expenditure of labor has been heretofore involved in conveying the aggregate from the various piles to the mixer.

It is primarily the object of the present invention to provide an apparatus whereby the aggregate may be mechanically conveyed from the various piles to the mixer, and inasmuch as the aggregate in road paving operations is usually disposed in relatively long piles extending longitudinally at the sides of the road it is more particularly an object to provide a conveying apparatus which will operate over relatively large areas without changing the position of the body portion of the apparatus. In view of the comparative rapidity at which road-paving operations proceed, it is necessary to procure a frequent shifting of the concrete mixer and consequently of the loading machine, in some operations this shifting occurring about once every twenty minutes, and it is therefore also an important object of the invention to provide a loading machine which is exceedingly mobile to provide for frequent shifting movements, and to provide for its transportation generally.

The present invention contemplates the accomplishment of the foregoing operations by the provision of a main longitudinal conveyer means and lateral conveyers movable longitudinally thereof and arranged to dis-

charge thereon, and it is further an object of the invention to provide an arrangement in which the lateral conveyers are capable of horizontal pivotal movement whereby they are adapted to engage all portions of an elongated pile of aggregate to convey the contents thereof, it being more specifically the object to provide an arrangement whereby the lateral conveyer members may be manipulated for horizontal movements from a single central point to procure actuation thereof in their various longitudinal positions along the main conveyer means.

Another object resides in the provision of a mounting for the lateral conveyer members whereby they may move vertically relative to the main conveyer means, to compensate for possible irregularities in the ground over which they travel.

Concrete aggregate usually comprises sand and gravel and in the operation of the present machine, one of the elongated piles at the side thereof would comprise sand and the other pile would comprise gravel. In concreting operations it is essential to procure definite relative proportions of these different ingredients conveyed to the mixer and in differing instances these proportions must be varied, these variations often being necessary at different times during a single concreting operation. It is therefore another important object of the present invention to provide an independent measuring means associated with the discharge of each of the lateral conveyer members, whereby the relative desired amounts of material conveyed may be determined, and it is in this connection further an object to provide a means for adjusting the measuring means.

A more detailed object of the invention resides in the provision of a common drive means for both the lateral conveyer members, whereby an economy of structure is procured and further whereby a single tightening device may be utilized to assure proper cable tension with respect to the lateral conveyers. In this connection it is also an object to provide an arrangement wherein the direction of travel of the cable portions in engagement with the lateral conveyers is always the same whereby the drive cable in addition to operating the elements of the conveyers also serves to urge the conveyers toward one end of the machine.

The present machine is adapted to discharge directly into the conventional loading skip of a mixing machine, and it is a further object of the invention to provide a suitable chute means for directing the aggregate from the main conveyer means into the usual skip of the mixer which means is movable to permit tilting movement of the skip in dumping into the mixer, and which is further automatically movable back to operative position upon the skip being lowered into receiving position.

A further object resides in the provision of a machine which may be manipulated for all its conveying and measuring operations, in the manner broadly heretofore set forth, from a single point and by a single operator. In the drawings.

Figure 1 is a vertical sectional view of a loading machine embodying the present invention, this view being indicated by line 1-1 of Fig. 2.

Fig. 2 is a top plan view of the machine, with one of the lateral conveyers and its corresponding mechanism shown in dotted outline.

Fig. 3 is a transverse sectional view through the machine on the line 3-3 of Fig. 1, with both of the lateral conveyer structures shown in full detail.

Fig. 4 is a transverse sectional view on the line 4-4 of Fig. 2 and showing the control means for the various operations of the machine.

Fig. 5 is a sectional view on the line 5-5 of Fig. 2 through one of the lateral conveyers.

Fig. 6 is a diagrammatic view showing the arrangement of the drive cable for the lateral conveyers.

Fig. 7 is a diagrammatic plan view of the entire machine showing its method of operation in relation to a mixing machine.

Fig. 8 is a partly diagrammatic plan view of one end portion of a modified form of the machine wherein the measuring of the aggregate is procured in the stationary receiving hoppers of a common type of mixer, illustrated in conjunction therewith.

Fig. 9 is a partly diagrammatic side view showing this modified form of machine associated with the last mentioned type of mixer.

Referring now more particularly to the accompanying drawings, the loading machine illustrated in Figs. 1 to 7 thereof, comprises an elongated wheeled body frame A which carries a longitudinal conveyer belt B arranged to discharge at one end of the frame and to receive the discharge of hoppers C mounted on carriages independently movable longitudinally of the frame and each carrying a downwardly extending lateral conveyer D for filling the hoppers from piles of aggregate disposed at the

sides of the frame. Means for controlling the operation and movement of the lateral conveyers and for dumping the hoppers are all disposed at one end of the machine.

The main frame comprises channeled side sills 10 and a central sill 11 connected by the plurality of transverse sills 12 which are grouped adjacent the ends of the frame. Wheeled axles 13 are carried by brackets 14 depending from the ends of the frame, and one of these axles is preferably steerable although no specific structure is shown in this connection. The central sill 11 serves chiefly as a track for the hopper carriages and terminates at the innermost cross sills 12. 70 75 80

Inasmuch as the lateral conveyer structures are similar, only one will be described and the numerals applied thereto are equally applicable to both.

The carriage of each lateral conveyer 85 mechanism comprises a U-shaped frame 15 at the ends of the arms of which are carried wheels 16 mounted on the corresponding side sill and the central sill and flanged to retain their engagement therewith. Carried within the frame 15 is a hopper 17 having its outer side wall inclined inwardly toward its bottom whereby the hopper may discharge well inwardly of the machine onto the main conveyer. 90 95

For supporting and driving the lateral conveyer associated with this hopper, a bracket 18 of inverted U-shape is carried at the inner side of the frame 15 and from the upper portion of this bracket, an arm 19 extends diagonally over the frame toward the forward end of the machine and forms a bearing at its free end for one end of a lateral conveyer shaft 20 which has its other end journaled in a bearing 21 on a bracket 22 upstanding from the outer side of the frame. At its angle adjacent the corner of the hopper the bracket arm is provided with a pair of upward and a pair of downward projections 26 which carry pairs of opposed pulleys 27 and pivoted to the bracket arms centrally between the pulleys is a horizontally swingable knuckle 28 to which is pivoted for vertical movement a lateral conveyer frame comprising side bars 29 between the outer ends of which is mounted an idle sprocket wheel 30, a drive sprocket wheel 31 is carried on the shaft 20, and trained about these sprocket wheels is an endless chain 32 carrying conveyer buckets 33 at spaced intervals, the upper and lower stretches of the chain passing between corresponding pairs of rollers 27 and held therebetween to effect proper operation of the chain upon horizontal swinging movement of the lateral conveyer frame which is permitted a universal pivotal movement. To support the outer end of the frame, transverse bars 34 are secured thereto, adjacent its outer end and extend at the 100 105 110 115 120 125 130

sides thereof and carry vertical bars 36 which carry at their lower ends swiveled ground wheels 37.

- The lateral conveyer thus extends downwardly and laterally of the machine from the hopper, and is adapted to pick up material from a pile of aggregate and to convey it to the hopper. By reason of the universal pivotal connection of its frame, the lateral conveyer may move vertically to compensate for irregularities in the ground over which it travels and may also move horizontally whereby to engage all parts of the pile of aggregate.
- For effecting this horizontal movement of the lateral conveyer in various positions thereof, a shaft 38 is extended longitudinally of the machine adjacent the intermediate portion of the inclined outer side of the hopper and journaled at its ends in the innermost cross sills 12. Splined on this shaft is a pulley 39 which is rotatably held for movement with the lateral conveyer carriage by a bracket 40 upon the side of the hopper.
- A pair of idle pulleys 41 are mounted on a common stub shaft 42 secured to the upper portion of the hopper above the pulley 39 and at the three corners of the frame are mounted pulleys 43; a cable 44 is trained about the shaft actuated pulley 39 and about the idle pulleys 41 and about the pulleys 43 at the corners of the frame and the ends of this cable are secured to a transverse bar 45 fastened to the lateral conveyer frame adjacent its inner end, the outer side of the bar being extended a considerable distance from the frame whereby a proper leverage is afforded to swing the frame horizontally upon pulling the cable. By the foregoing arrangement the lateral conveyer may be swung horizontally in its various positions along the machine by rotating the shaft 38. This shaft 38 is controlled, in common with various other operating members hereinafter described, from a common point at the forward end of the machine, and to provide bearings for various shafts associated with these control means, an upstanding frame 46 of inverted U-shape is carried adjacent the forward end of the machine and has extending from its sides, forwardly and downwardly extending angular bars 47 connected adjacent their angle by a transverse bar 48. The shaft 38 is controlled by a shaft 49 having a bearing in one of the sides of the frame 46 and in the transverse bar 48, this shaft 49 carries at its forward end a hand wheel 50 and has a sprocket connection 51 with the shaft 38. Thus rotation of the hand wheel 50 will swing the lateral conveyer horizontally to engage different portions of the pile of aggregate.

For moving the carriage longitudinally of the machine, a shaft 52 is journaled transversely on the angular bars 47 and loosely

mounted on this shaft is a hand wheel 53 having sprocket teeth on its hub, a sprocket chain 54 is secured at one end to the forward end of the inner side of the carriage and extends forward of the machine and about an idle pulley 55, and then upwardly and about the sprocket wheel 53 and then downwardly about a pulley 56 disposed below the pulley 55 then rearwardly and about the idle pulley 57 at the rear end of the machine and finally forwardly for securing to the rear end of the frame. Thus upon rotating the hand wheel 53, the carriage and consequently the hopper and lateral conveyer are shifted longitudinally of the machine.

The hopper is provided with a dump bottom comprising two sections 58 hinged at the outer sides of the hopper, and to provide a means operable from the forward end of the machine for dumping the hopper in its various positions along the machine, a shaft 59 is journaled transversely on one end of the hopper and this shaft carries a crank arm 60 to which is secured the upper end of a span link 61 having chains 62 secured to its lower end and to the bottom sections of the hopper. The shaft 59 extends inwardly of the hopper and carries on its inner end a pulley 63. Loosely mounted on the shaft 52 at the forward end of the machine is a second hand wheel 64 having a sprocket hub and trained about this sprocket hub is a sprocket chain 65 which extends downwardly thence about an idle pulley 66 and rearwardly to the rear end of the machine, thence forwardly and about the pulley 63 on the shaft 59, thence forwardly and about an idle pulley 68 and finally upwardly and about the sprocket hub of the hand wheel 64. Thus upon rotating the hand wheel, a movement of the shaft 59 will be effected to open or close the bottom of the hopper, it being noted that during the movements of the hopper toward the forward end of the machine, its bottom will be held closed and the hand wheel 64 will rotate idly.

To drive the lateral conveyer, a beveled gear wheel 69 is carried on the inner end of the shaft 20 and meshes with a beveled gear 70 which is carried on a shaft 71 journaled at the intermediate portion of the bracket arm 19 and at the upper portion of the inverted U-shaped bracket 18. On the inner end of the shaft 71 is a cable sheave 72 and idle sheaves 73 are carried by the sides of the bracket 18 to hold a cable in proper frictional contact with the sheave 72. A clutch member 74 is splined on the shaft 71 and engageable with the sprocket wheel 70 to rotate it and thus procure operation of the lateral conveyer, and to provide for operation of this clutch in the various positions of the carriage, a longitudinal shaft 75 is provided having its forward end journaled in an upper corner of the frame 46 and

- carrying a crank handle 76 whereby it may be rotated, and having its rear end journally supported by an upstanding bearing frame 77 at the rear end of the machine, the shaft 5 being disposed under the clutch member, and having splined thereon a clutch yoke 78 embracing the clutch member and properly held with relation thereto by its confinement between bearing arms 79 extending 10 downwardly from the bracket 18 to embrace the shaft 75. Thus upon reciprocating the crank handle 76, the operation of the lateral conveyer may be controlled.

Each of the lateral conveyers and its associated mechanism is thus adapted for entirely independent operation.

- Transversely mounted on the body frame rearwardly of the upstanding bearing frame 77 is the main drive shaft 80 of the machine which may receive its power from any suitable source as by an engine carried on the frame. This shaft carries at its central portion a drum 81. A second drum 82 is mounted on a transverse shaft 83 journaled 20 on the bearing frame 77 and disposed adjacent the first drum, and associated with these drums and with both of the drive sheaves 72 of the lateral conveyer structures is a common cable 84 which extends 25 from the top of the drum 81 over the drum 82 then under the adjacent guide over the drum 82 then under the adjacent guide sheave 73 of one of the lateral conveyers over the drive sheaf 72 under the other 30 guide sheave 73 thence forwardly around a pulley 85 at the forward end of the machine, thence rearwardly around an idle pulley 86 mounted on the shaft 83 at the rear end of the machine, thence forwardly 35 under the adjacent guide sheave 73 of the other conveyer member, thence over the drive sheave 72 of said other conveyer and under the other guide sheave 73 thence forwardly and around a vertical idle pulley 40 45 87, thence rearwardly around the drum 82 and finally the cable is given a number of turns on both the drums 81 and 82 whereby its proper frictional engagement therewith is assured.

- 50 Thus those portions of the cable which engage the drive sheaves 72 both drive in a forward direction and in addition to operating the lateral conveyers, the frictional engagement of the various sheaves with 55 these cable portions serves also to advance the conveyers and their associated mechanisms whereby they are at all times urged to proper operative engagement with the piles of aggregate.

- 60 The pulleys 85 and 87 which carry the cable loops of the drive sheaves 72 are provided with a common adjusting means to procure desired tension of the cable and to accomplish this, an upstanding bearing frame 88 is carried by the central sill 11

of the main frame inwardly of and adjacent the bearing frame 46 and carried by these frames are a spaced pair of shafts 89 on which are slidably mounted bearing sleeves 90 formed at the arms of a U-shaped carriage 91. The vertical pulley 87 is disposed between and journally connected with the arms of this carriage and the horizontal pulley 85 is journaled on the bight of this carriage. Fixedly secured to the bight of 75 the carriage is the shaft 92 which is projected through a transverse bar 93 on the frame 46 and an adjusting wheel 94 is threaded on the outer end of this shaft to thus hold the carriage against movement 80 and to consequently hold the cables under desired tension.

The main conveyer comprises a broad endless belt 95 having sprocket chains 96 at its sides which at one end of the conveyer are trained about the sprocket wheels 97 carried on a shaft 98 which is journaled in brackets 99 projected from the end of the body frame. At the other end of the conveyer, the chain and belt are trained 90 about idle wheels 100 carried by a shaft 101 which is in turn carried by a pair of side bars 102 which have their rear ends directed upwardly at 103 for securement to one of the transverse sills 12 of the main 95 frame and which are supported at their forward ends by attachment to downward extensions of the front axle brackets 14. The upper stretch of the main conveyer belt 95 is supported by rollers 104 carried by the 100 side bars 102 and immediately forwardly of the rear axle 13 of the body frame, guide rollers 105 are disposed over the sprocket chains 96 of the belt whereby the major portion of the belt is held in horizontal position, with its rear portion inclined upwardly, idle rollers 106 being disposed between the stretches of the belt adjacent the rear axle to guide the lower strip of the belt.

Appreciating that the manual operation 110 of conveying aggregate from the piles to the mixer is divided into two steps, that of loading the usual wheelbarrows, and of trundling said barrows to the mixer, it is seen that the lateral conveyers D of my 115 machine are the mechanical equivalent of the barrow loading step, while the main conveyer B is the mechanical equivalent of the trundling step of the complete conveying operation, and inasmuch as the barrows in the manual operation were utilized to measure the aggregate, by counting the number of barrow loads so the hoppers C serve to more accurately measure the aggregate in my machine. Thus, while it is 125 highly desirable to use the lateral conveyers to mechanically discharge the loading function, it may be under certain conditions advisable to eliminate said lateral conveyers whereby the machine would effect mechani- 130

cally the main conveying step, the hoppers being loaded manually.

To provide an arrangement whereby the loading skip of a concrete mixer designated at X in Fig. 7 may be permitted its usual free movement to dump into the mixer, the brackets 99 are extended past the main conveyer shaft 98, and are downwardly inclined therefrom and carry at their free ends a shaft 110 on which is fixedly secured a chute plate 111 projecting inwardly of the edge of the skip. An arm 112 projects downwardly from the central portion of the shaft at approximately a right angle to the chute plate, and at one side of the shaft 110, an arm 113 projects rearwardly therefrom carrying a weight 114. The plate is normally disposed in its inclined position to discharge into the skip, being held against rotation by a stop arm 115 on the shaft engageable with one of the brackets 99. When the skip is raised to procure its dumping operation, it engages the plate 111 and swings it upwardly. In this move, the weight arm 113 swings inwardly of the dead center afforded by the shaft 110 and the arm 112 moves rearwardly into the path of the skip, rotation of the shaft in this direction being limited by engagement of a stop arm 117 carried thereby, with one of the brackets 99. Thus upon return movement of the skip to its loading position it will engage the arm 113 and trip the shaft whereby the arm 113 will be swung rearwardly of its dead center and the plate permitted to fall to its operative position.

Fig. 7 shows the operative position of the present machine between two piles of aggregate Y and in advance of the mixer M.

In operation, the lateral conveyers are manipulated to engage their corresponding piles of aggregate. Thus, in operation both of the lateral conveyer members are actuated simultaneously. Upon the smaller hopper being filled, the operator stops the corresponding conveyer by shifting the clutch 74 thereof and the other lateral conveyer continues in actuation until the larger hopper is filled at which time both of the hoppers are dumped in the manner heretofore set forth and the operation is repeated. Thus different relative amounts of aggregate ingredients may be conveyed. Inasmuch as it is necessary to vary the relative proportions of material conveyed, an independent adjusting means for the contents of the hoppers is provided which comprises in connection with each hopper, a transverse partition plate 118 selectively engageable between corresponding pairs of a plurality of series of pins 119 within the hoppers.

It may in some instances be desired to use the present machine in connection with that type of concrete mixer designated at M' in Fig. 9 and provided with a stationary load-

ing hopper L', divided into two sections 121 and having their tops disposed at a considerable elevation. To adapt the machine for this type of mixer, the main conveyer is provided in two sections B' each adapted at its rear end to discharge into a corresponding hopper section 121 and in this form, the hoppers 17 of the carriages are eliminated and last lateral conveyer discharges directly on to its corresponding conveyer section B'. 75

I claim:

1. A loading machine including a longitudinally extending conveyer, a lateral conveyer longitudinally movably carried by the machine, and universally pivotally movable 80 with respect thereto and arranged to discharge on the longitudinal conveyer and a wheeled support for the free end of the lateral conveyer.

2. A loading machine comprising an elongated wheeled body frame, a longitudinal conveyer carried by said frame, and a lateral conveyer carried by said body frame for horizontal and vertical pivotal movement and for longitudinal movement with respect 90 thereto and adapted to discharge on the longitudinal conveyer.

3. A loading machine including a main wheeled frame including side and end sills, a central sill carried by the frame, wheeled 95 carriages mounted on the side and central sills, measuring hoppers on said carriages, lateral conveyers carried by said carriages and arranged to discharge into said measuring hoppers, and main means for conveying 100 carried by the main frame and adapted to receive the discharge of said measuring hoppers.

4. A loading machine including a main wheeled frame having side and end sills, a central sill carried by the frame, hoppers disposed between the side and central sills, wheels supporting said hoppers and mounted on said sills, lateral conveyers arranged to discharge into the hoppers and movable 110 therewith and longitudinally extending means for conveying carried by the frame and disposed under said hoppers.

5. A loading machine including a main longitudinal means for conveying, lateral 115 conveyers movable longitudinally of the main means for conveying, wheels movable with the lateral conveyers for operating them and a common drive cable in connection with both wheels.

6. A loading machine including a main means for conveying lateral conveyers movable longitudinally of the main conveyer, wheels movable with the lateral conveyers for operating them, a common drive cable 125 in connection with both wheels, and clutch connections between the wheels and the corresponding lateral conveyers.

7. A loading apparatus including a main means for conveying lateral conveyers mov- 130

- able longitudinally of the main means for conveying, wheels movable with the lateral conveyers for operating them, a common drive cable engaged with both wheels, and 5 those portions of the cable which engage the said wheels being arranged to travel in the same direction whereby both lateral conveyers are urged toward one end of the machine.
- 10 8. A loading machine including a longitudinal main conveyer, a lateral conveyer movable along the main conveyer and adapted for horizontal movement, and means operable from a single point for horizontally 75 swinging said lateral conveyer in various longitudinal positions thereof.
9. A loading machine including a main conveyer, a hopper movable longitudinally over the main conveyer, a lateral conveyer 20 arranged to discharge into said hopper, and means operable from a single point for dumping said hopper in various longitudinal positions thereof.
10. A loading machine including a main 25 means for conveying, lateral conveyer members arranged to convey material to the main means for conveying and movable longitudinally of the main means for conveying to hoppers each adapted to measure the discharge of a respective lateral conveyer and independent control means for the actuation 30 of the lateral conveyer members in various positions thereof and operable from a single point.
- 35 11. A loading machine including a main conveyer, a carriage movable longitudinally of the main conveyer, a lateral conveyer connected at its inner end to the carriage for horizontal pivotal movement and arranged 40 to discharge on the main conveyer, a longitudinal shaft, a member splined on the shaft and movable with the carriage and means connecting said member and the conveyer for procuring horizontal pivotal movement thereof upon rotation of the shaft.
12. A loading machine including a main conveyer, a carriage movable longitudinally of the main conveyer, a lateral conveyer connected at its inner end to the carriage 45 for horizontal pivotal movement and arranged to discharge on the main conveyer, a longitudinal shaft, a pulley splined on the shaft and movable with the carriage, pulleys carried by the carriage and a cable connected with the lateral conveyer at the sides thereof, and trained about all of the pulleys whereby rotation of the shaft will procure horizontal swinging movement of the lateral conveyer.
- 50 55 60 65 13. A loading machine including a main conveyer, a carriage movable longitudinally of the main conveyer, a lateral conveyer connected with the carriage for movement therewith and arranged to discharge on the main conveyer, a drive wheel on the carriage, a drive wheel for the lateral conveyer, a clutch connection between the two drive wheels, a shaft extending longitudinally of the main conveyer and an arm splined on said shaft and connected with said clutch for operating it.
14. A loading machine including a main conveyer, hoppers movable longitudinally of the main conveyer, and arranged to discharge thereon, lateral conveyers movable with the hoppers and arranged to discharge thereinto, and means for independently adjusting the capacity of said hoppers. 70
15. A loading machine of the class described including an elongated wheeled frame, a longitudinally extending means for conveying carried by the frame, and a plurality of measuring hoppers longitudinally movable on the frame and arranged to discharge on said main conveying means. 80
16. A loading machine comprising a main longitudinal means for conveying, lateral conveyers arranged to convey material to the main means for conveying and movable longitudinally of the main means for conveying, means for independently measuring the discharge of the lateral conveyer members, and independent control means for the actuation of the lateral conveyer members. 85
17. A loading machine comprising a frame, a pair of carriages connected therewith for travel longitudinally of the frame, means for controlling the position of each of said carriages independently of the other, a means for conveying below each of the carriages, an elevator connected with each carriage, means for independently measuring the discharge of said elevators, and means for independently controlling the actuation of said elevators. 90
18. A loading machine including a frame, a pair of elevators adapted to pick up material from the ground and discharge same at a higher level, means carried by and movable longitudinally of the frame for adjusting said elevators horizontally back and forth, means for measuring the material discharged by said elevators and means for conveying the material discharged from the elevators to one end of the machine. 95
19. A loading machine of the class described including an elongated wheeled frame, a longitudinally extending means for conveying carried by the frame, and a pair of hoppers longitudinally movably mounted on the frame, said hoppers having differential capacities and being adapted to measure material for discharge onto said longitudinally extending means for conveying. 105
20. A loading machine including a main 100 means for conveying, hoppers movable longitudinally thereof and arranged to discharge thereon, lateral conveyers movable with the hoppers and arranged to discharge thereinto, and means for independently con- 110
- 115
- 120
- 125
- 130

trolling the operation of the lateral conveyors.

21. A loading machine including an elongated wheeled frame, a longitudinal means for conveying carried thereby, a lateral conveyer movable back and forth along the frame, and a measuring hopper interposed between the discharge end of the lateral conveyer and the main means for conveying

and adapted to receive material from the lateral conveyer and to discharge said material on the main means for conveying.

In testimony whereof I affix my signature, in the presence of two witnesses.
